Joseph R. Thomas, Chicago, Ill.

Application July 23, 1954, Serial No. 445,299

17 Claims. (Cl. 5—13)

This invention relates in general to convertible furniture and is more particularly described as a chair or davenport bed in which a plurality of foldably connected sections are movable from a position below and behind the seat to an aligned position extending outwardly from the seat frame.

In extending and returning the connected sections, they must be folded compactly in a certain predetermined manner and mounted to swing through a restricted space between a fixed back rest and a fixed front board. In the folding and unfolding movement within the frame, it is most convenient to retain the connected sections in a folded position as they swing into and out of the frame and the present invention relates particularly to a catch for engaging the folded sections either to be advanced continuously in one direction, or to be prevented from a backward movement once the sections are started in a folding or unfolding position or to be stopped at an intermediate position in both the folding and unfolding operations.

It is an important object of the present invention to provide stop means for arresting the movement of the connected sections so that the complete movement may be interrupted or made in stages which are more convenient in the folding and unfolding movements of the sections.

A further object of the invention is to provide a releasable catch by means of which the movement in stages may be readily effected.

A further object of the invention is to provide a roller at the top and inner side of the fixed front board for assisting the folded sections in passing over the top of the front board if they are improperly mounted in the frame, or if they tend to sag due to looseness of the joints or an unduly heavy enclosure of a mattress and bed clothes between the folded section.

A still further object of the invention is to mount the sections for swinging movement upon axes which are above the normal level of the seat so that the connected bed sections are swung highly within the frame in the initial movement of the seat section when it is intended to form a bed and in the last movement from the bed position when returning the sections to form a seat.

Other objects of the invention will appear in the specification and will be apparent from the accompanying drawings in which,

Fig. 1 is a sectional side elevation of a plurality of connected sections in their folded position within a seat frame to form a chair or davenport in accordance with this invention.

Fig. 2 is a similar view showing the sections of Fig. 1 in an initial position which they assume when the seat section is inverted rearwardly in the operation of changing the structure to form a bed or preliminary to the return of the folded sections to the seat frame from the bed position.

2

Fig. 3 is a similar view of the structure shown in Figs. 1 and 2 in the extended or bed position.

Fig. 4 is a perspective view showing an enlarged detail of the connections between the intermediate and seat section in the position shown in Fig. 3.

Fig. 5 is a sectional detail showing the connections between the intermediate and outer section in the position shown in Fig. 3.

Fig. 6 is a perspective view showing a latch in connection with one of the mounting links for holding the sections in the position shown by Fig. 2.

Fig. 7 is a perspective view of a portion of the seat section having a movable member to engage the latch shown in Fig. 6.

Fig. 8 is a view combining some of the details in Figs. 6 and 7 to show engagement of the member with the latch.

Fig. 9 is a perspective view similar to Fig. 6 showing a double latch for arresting the movement of the connected sections as shown in Fig. 2 in both directions of movement; and

Fig. 10 is a perspective view similar to Figs. 6 and 9 showing a latch for reverse engagement only of the folded and connected sections as shown in Fig. 2.

25 In the folding and unfolding movement of convertible furniture, it is sometimes possible to grasp a rail or a handle below the seat and to manually raise and move it outwardly from the frame in changing the structure from a davenport to a bed, in one continuous movement.

30 In collapsing the furniture, this movement is reversed. For persons who are unfamiliar with the folding and unfolding movements, it is rather difficult for them to effect these movements until they have practiced or become accustomed to such operations.

35 In the present invention, it is difficult to produce a single continuous movement of the connected sections for the added reasons that instead of the seat section pulling outwardly at the front of the other sections, the seat section in the present invention is mounted to overturn rearwardly within the frame so that the inverted seat section becomes the innermost section of the bed, the intermediate section which is disposed in vertical position behind and below the seat is moved in front of the seat section, and the section which is at the bottom of the

40 frame is swung outwardly in front of the intermediate section and becomes the outermost section of the bed.

45 Referring now more particularly to the drawings, a seat frame 12 of conventional type is represented as having side arms 14 (only one shown) connected at their rear by a back board 16 and connected at their front lower edges by a fixed upwardly extending front board 18. Extending downwardly at the rear of the frames is a fixed and usually upholstered back rest 20. The space between the lower edge of the back rest 20 and the upper and inner edge of the front board 18 is of fixed and limited dimensions in which the connected bed sections must be moved in changing the furniture from a seat to a bed.

50 The folding bed comprises a seat section 22, an intermediate section 24, and an outer section 26. These sections are commonly formed of angle bar side rails connected and reinforced for receiving a metal bed fabric in the intermediate and outer section and preferably flexible straps 30 extending across the seat section and longitudinally of the bed in bed position. These fabric and strap connections for supporting a bed mattress and bed clothes and also for forming the seat section are well known in this art and form no particular part of the present invention.

55 60 65 70 75 80 85 90 95 100 At the front of the seat section is a front rail 32 which extends at right angles thereto and matches with the top

of the front board 18 in closed position if desired. At the rear of the seat section (in seat position) is a metal bracket 34 riveted thereto in fixed position for supporting an angle bar 36 (see Figs. 3 and 7) bent at right angles and extending across the bed section to the other side thereof to provide a spacing and strengthening support for the rear side of the bed section.

Attached to the inwardly extending web of the angle bar 36 adjacent the side bar of the section 22 is a reverse angle bar section 38 which forms a rigid support for connecting the seat section to the intermediate section by a pair of members, one a lever 40 and the other a link 42. The link 42 is directly pivoted at one end to the adjacent end of the side bar of the intermediate section 24 and at its other end to the outer end of the angle bar 38. One end of the lever 40 is connected by a pivot 44 with the angle bar 38 and at its other end as clearly shown in Fig. 4, it is connected by a pivot 46 with the side bar of the intermediate section 24 at a short distance from the end to which the link 42 is pivoted. Thus the lever 40 and the link 42 form a double pivoting and hinging connection between the seat and intermediate sections.

A supporting leg 48 is pivoted at each side of the intermediate section 24 adjacent the end nearest the seat section and a leg 50 is pivotally connected at each side of the outer section 26 at a distance from the joint between the intermediate and outer sections. These legs are pivoted to fold flatly against the sections to which they are connected.

Between the intermediate and outer sections is a connecting plate 52 fixed to the inner end of the outer section by rivets 54 and having a pivot 56 for engaging the adjacent end of the intermediate section 24 so that they may swing apart at right angles to each other. A portion of the plate 52 extends below the sections and provides a pivot 58 for one end of a lever 60 which is connected to the lever 40 at a short distance from its pivotal connection with the intermediate section by a pivot 62. A short leg operating link 64 is connected at one end to the upper portion of the leg 48 and at the other end of the lever 60. A link 66 is connected near the upper end of each outer leg 50 by a pivot 68 and the other end of this link is connected by a pivot 70 with the lever 60 at a distance from its pivot 58 by which it is connected to the pivoting plate 52.

With this construction, a movement of the intermediate and outer sections from a position at right angles to each other as shown in Fig. 1 in which the legs are folded substantially against the sections, the legs are automatically extended because of the connection of the levers 40, 60 and the link 66 so that when the bed sections are extended, they will assume a substantially right angled and supporting position as shown in Fig. 3.

The connected bed sections may be completely assembled before they are applied to a supporting frame 12 or they may be partially assembled and connected in the frame and then the parts connected together. The only mounting for the connected sections is between the seat section 22 and the sides of the frame 12 and comprises a strap 72 attached at each inner side of the supporting frame and extending from the lower side of the frame at a distance from the front to a location behind and slightly above the lower end of the fixed back rest 20. Mounted upon a pivot 74 at the upper end of the mounting strap 72 is a lever 76 preferably in the form of a bell crank having its other end connected by a pivot 78 with an angle bar 80 secured to the side frame of the seat section 22. The angle of the bell crank lever 76 is located at such a point that it will extend around the lower edge of the fixed back rest 20 in a raised position of the seat section and the connected sections as shown in Fig. 2. At the other end of the mounting strap 72 is a pivot 82 which is connected to one end of another

mounting lever 84 which has a pivot 86 at its other end connected to the extremity of a fixed support 88 which extends slightly above the seat fabric 30 in the seat position as shown in Fig. 1 and slightly behind the lower end of the fixed back 20 in the seat position. The fixed support 88 may be secured to the angle bar 80 attached to the seat section 22 or may be an extension of it.

Thus it will be noted that both of the pivots 78 and 86 upon which the seat section is inverted are located above the upper level of the seat fabric. The result of this construction is to throw the connected seat sections high in the frame as shown in Fig. 2 when the seat section to which they are connected is overturned rearwardly. To balance and counter-balance the movement of the seat sections by means of the levers 76 and 84, a coil spring 90 may be connected at one end to the lever 76 near its pivot 74 and over the other end to a bracket 92 fixed to the lower side of the seat frame 12, and a coil spring 94 may be connected at one end to the lever 84 near its pivot 86 and the other end may be connected to a fixed point 96 on the side arm above the top of the front board 18 and inwardly from the front edge of the side arm. The bracket 92 also acts as a stop for the lever 84 in the folded position as shown in Fig. 1.

In the position shown by Fig. 2, spacing of the connected sections in their right angle position with the intermediate section spaced from the seat section and the outer section also spaced from the seat section is assured by the outer leg 50 which through its link 66 locks the sections 22, 24 and 26 in this position. A projection 98 at the outer end of section 26 extends at right angles to the section and limits the movement of the outer section 26 toward the seat section at its under side. In this locked position as shown in Fig. 2, the folded sections are substantially balanced, the tendency of the combined springs 90 and 94 being to swing the sections slightly inward.

In order to prevent the folded sections from swinging inwardly, and to hold them in raised or intermediate position as shown in Fig. 2, a latch 100 is pivoted at the angular corner of the angle bar 36 as shown more clearly in Figs. 7 and 8, by means of a pivot 102 extending through the inwardly extending web of the angle bar close to the corner thereof. This latch is preferably of flat sheet metal having a bent portion 104 at the end opposite the pivot and with a straight portion 106 adjacent the bent portion. In the straight portion is a perforation 108 to receive one end of a coil spring 110, the other end of which is attached to a perforation 112 in the inwardly extending web of the angle bar 36. The spring tends to pull the latch from an outward position shown in broken outline to an inner position in which the extremity of the bent portion 104 which is adjacent the straight portion 106 abuts the outer side of the angle bar 36 as shown more clearly in Fig. 8.

Attached to one of the side mounting levers 84 is a detent 114 having an inclined edge 116 forming a shoulder 118 and connected to the lever by rivets 120 or any other suitable manner in the path of a lower tail end 122 of the latch 100. The connection of the detent is at an angle to engage the tail end 122 of the latch when the folded sections are swung upwardly into the position shown by Fig. 2, the tail end of the latch engaging and riding up on the angular surface 116 and swinging the latch until the shoulder 118 is reached whereupon the latch is pulled in engagement with the shoulder of the detent by the spring 110 as shown more clearly in Fig. 8. In this position, the springs 90 and 94 may be adjusted to hold the folded sections together and against the shoulder of the detent whereupon the folded sections may be held with a light spring tension in the position shown by Fig. 2 and against outward movement.

At this time, the operator of the bed davenport is ready to grasp the upper end of the outermost bed sec-

tion and to swing it outwardly and forwardly unfolding the sections in accordance with the connections between the sections and automatically extending the legs to a supporting position when the sections are extended in alignment as shown in Fig. 3. Before he can effect the return movement, he must release the latch 100 from engagement with the shoulder which he does by inserting his hand between the side arm 14 and the bed sections which are in the position shown in Fig. 2 until he reaches the latch 100 and presses it downwardly so that the tail end 122 of the latch is rocked out of the path of the shoulder 118, whereupon the folded sections may be rocked downwardly and under the seat section into the frame, as described.

Instead of the detent having a single inclined surface as shown in Fig. 6, a detent 124 as in Fig. 9 may be secured to the lever 84 having two inclined surfaces 126 and 128 extending upwardly from opposite directions and terminating at their center in a notch 130. This detent provides means for engaging the folded sections in both directions of movement when they reach the approximate position as shown in Fig. 2 so that it is necessary to manually release the latch 100 for continuing the movement of the folded sections in either direction from this position.

Similarly, if desirable, a detent 132, as in Fig. 10, may be provided attachable as before to the lever 84 having an inclined surface 134 extending from the outer end inwardly and opposite to the inclination of the detent 114, and having an inner shoulder 136 to engage the latch 100, if the tendency of the spring mounting means is to swing the folded sections outwardly in the position shown in Fig. 2. The shoulder 136 of the detent 134 may be engaged in the particular movement of the folded bed sections to the approximate positions of Fig. 2 and to swing it outwardly therefrom, the latch must be manually engaged to raise it over the shouldered end of the detent. Upon the return movement in manually swinging the sections inwardly from the bed position, the latch 100 will engage the inclined surface 134 until the shoulder is reached and this will hold the sections from swinging outwardly whereupon the folded sections may then be continued in their movement within the frame and into folded or seat position.

With all of these constructions, the folded sections within the frame are raised from the front of the frame and swung upwardly to an intermediate position and then it is necessary to substantially reverse the direction of movement to move the sections outwardly into extended or bed position. Likewise, in the reverse operation, the extended sections are raised at the outer end and are swung upwardly and inwardly toward the frame until they assume the folded position as shown by Fig. 2. At this point, it is necessary to substantially reverse the movement of the sections and to swing them outwardly, downwardly and inwardly into the frame below the fixed back 20 and over the top of the fixed front board 18.

When the folded sections are housed within the frame, an angle bracket 138 is secured to the inside lower edge of each side arm 14 which has an inward extension 140 to engage below the outer section 26 or its leg 50 which is folded against it in this position. The bed or chair frames are commonly supported upon casters or short legs which elevate the bottom of the frame from the floor or other surface upon which the frame is supported so that some of the parts may extend slightly below the frame as shown in Fig. 1.

To prevent engagement of any of the connected sections with the top of the fixed front board 18, a roller 142 is supported at the top of the inner edge thereof by a bracket 144 in such a position that it will not obstruct the front rail 32 attached to the seat section and will act as a guide for holding the front of the seat section in place. From the position of the folded sections in Fig.

2, it is apparent that the parts of the folding sections when swung upwardly to this folded position are swung clear of engagement with the top of the front board and also clear from engagement with the rollers 142, but in swinging outwardly therefrom, if the folded sections are filled with bed clothes, these may tend to bulge outwardly and if the connections between the sections happen to be slightly loose, some of the section parts may tend to move downwardly and might otherwise scrape the top of the fixed front board 18 if this precaution is not taken.

Since the back rest 20 extends forwardly and downwardly from the back of the frame, and the fixed front board extends upwardly at the front of the frame, there is a limited distance between these parts between which the folding sections must move. The seat section is supported at the front in seat position by the engagement of the seat section front rail 32 and the fixed front rail 18 of the frame and the disposition of the mounting levers which support the seat section upon the pivots 78 and 86 is such that the rigid support formed by the angle bar section 38 in its upward or seat position is behind the lower end of the fixed back rest 20, and in fact extends considerably above the lower end of the back rest. This construction and mounting makes it necessary to invert the seat section rearwardly and at the same time to swing it forwardly in order to move it upwardly and outwardly in the restricted space between the lower end of the back rest and the top of the fixed front rail.

Likewise, the intermediate section 24 and the outer section 26 which are connected together and to the seat section by means of the lever 40 and the link 42 must likewise be moved initially in the same reverse direction with the seat section. The movement together of the seat section and the outer section is limited by the projection (or projections) 98 and the sections may be locked in this folded position by the movement of the outer leg (or legs 50) beyond the center line connecting it to the lever 60 as defined by their pivots 58 and 70. In this folded position, the outer and seat sections substantially form the outer length of a hollow L, the lower or shorter end of which is formed by the intermediate section, the fixed supporting angle bar 36 and the connecting lever and link 40 and 42.

In operation, the folded sections are thus mounted for rearwardly overturning movement in a counter-clockwise position as shown in Fig. 2, until they reach the substantially balanced condition. In the first stage of operation and if desired, a releasable detent may be provided normally restraining the folded sections from continued movement in one direction or the other so that in the next stage of the operation of unfolding the sections and extending the bed, the outer section or the legs 50 of the outer section may be grasped and pulled reversely to the original movement or outwardly from the frame, the manual pulling on the outermost section thus releasing the locking action of the legs 50 or the legs being positively released by pulling outwardly upon them. This outward movement is then continued, the weight of the sections when unfolding being sufficient to overcome any tendency of the springs 90 and 94 to return the structure within the frame.

In folding the structure from the extended or bed position, the above operation is substantially reversed; the outer end of the outer bed section 26 is manually raised which breaks the locking connection for the legs between the links 66, 60 and the lever 40 which is connected to the seat section. This in turn allows the outer and intermediate sections 26 and 24 to assume a right angle position with respect to each other and to automatically fold their legs 50 and 48 respectively against the bottoms of the sections and swinging the seat section 22 upwardly upon its mounting levers 76 and 84. With the sections thus assembled in the intermediate stage as shown

in Fig. 2, they are ready for a reverse movement swinging the shorter end of the L first into the frame below and behind the lower end of the back rest 20 and at the same time swinging the seat section and the outer section together inwardly above the top of the fixed front board 18 until these two sections are substantially parallel with the bottom of the frame and the short end of the L is in its folded position above and behind the lower end of the fixed back rest.

To return the folded structure from the intermediate stage, it may be necessary to release the detent before the reverse returning movement of the folded frames can be effected.

The seat section and the connected sections are thus mounted for joint overturning movement upon the mounting members as 76 and 84 and the connected sections 24 and 26 are guided in their movements by links and levers which connect them for positive and predetermined movements but in their folding and unfolding operations so that the relative movements of the sections are entirely automatic and predetermined, no manual adjustment or different operation being possible once the sections are set up and properly connected within a frame. The only connection with the folding sections and the frame is through the mounting members 76 and 84 and they in turn are connected to the ends of a mounting strap 72 at each inner side of the supporting frame to insure proper spacing of the mounting parts and to provide a simple means for connecting the folding sections at the inside of a frame.

While a preferred construction has been thus described in some detail, it should be regarded as an illustration or example rather than as a limitation or restriction of the invention, since various changes in the construction, combination and arrangement of parts may be made without departing from the spirit and scope of the invention.

I claim:

1. Convertible furniture having a frame with a fixed back rest extending downwardly and forwardly from the back to provide a space behind and below the lower end of the back rest and a fixed front board extending upwardly at the front of the frame providing a limited space in the frame between the lower end of the back rest and the top of the front board, a plurality of connected seat and bed sections foldable into a hollow angular structure extending below the seat section and upwardly at the rear of the frame below and behind the lower end of the back rest, means mounting the seat section for swinging it and the other sections upwardly together to a predetermined set position to clear the top of the fixed front board and to swing the portions from behind and below the back rest to a position in front of the back rest but free from contact with the front board, and means connecting the sections for swinging them oppositely outward from the said predetermined position to separate the sections to extend them into alignment and to overturn the seat within the frame.

2. Convertible furniture in accordance with claim 1, having stop means connected to the seat section and one of the said mounting means for releasably holding the folded seat sections in the predetermined set position.

3. Convertible furniture in accordance with claim 2, in which the stop means comprises a detent on one of the mounting means and a latch projecting from the seat section and engaging the detent when the seat and connected sections are rotated to the predetermined set position before the sections can be swung oppositely.

4. Convertible furniture in accordance with claim 2, in which the means connecting the sections comprises the links and levers for locking the sections together in the predetermined set position so that the connected sections may be retained in this position in swinging into and out of the frame in the said restricted space between the back rest and the fixed front board.

5. Convertible furniture in accordance with claim 3,

in which the detent has an inclined contact surface and the latch is pivoted and spring pressed to engage the detent in one direction of movement, and the latch must be manually released to continue the movement of the sections.

6. In convertible furniture in accordance with claim 3, spring means connected between the mounting means and the frame for counter-balancing the seat and connected sections in their movement to and from the predetermined set position, the spring means having a tendency in the set position to further invert the folded sections and the latch opposing said further inverting movement, the latch being manually releasable from the detent before the sections are released for and extending movement forwardly and oppositely from the set position.

7. Convertible furniture in accordance with claim 6, in which the spring means tends to swing the folded sections outwardly in opposition to their direction of swinging movement in the frame and the detent for engaging the latch being disposed to engage and restrain the folded sections from movement in the outward unfolding direction until the latch is manually released.

8. Convertible furniture in accordance with claim 6, in which the detent has two portions inclined oppositely from the center and a notch in the center for engaging the latch which projects from the seat section in both directions of movement of the connected sections in folding and unfolding at the said predetermined set position so that the latch must be manually disengaged from the detent before the folded sections can be moved in either direction from the said set position.

9. In convertible furniture, the combination with a frame having side arms, a back rest extending from the top downwardly between the arms and a fixed front board extending upwardly at the front of the frame between the two side arms, of a foldable bed bottom comprising connected seat, intermediate and outer sections adapted to be extended from a folded seat position within the frame to a bed position with the sections in alignment within and extending in front of the frame, the sections when folded within the frame being of a height to pass into and out of the frame between the lower end of the back rest and the top of the front board and sufficient to form a seat support with the outer section below the seat and the intermediate section extending upwardly at the back of the frame behind and below the lower end of the back rest, and the seat and outer sections being of a length longer than the distance between the lower end of the back of the seat and the top of the front board, means including a pair of members connected to the inside of each arm rest and to the side of the bed section for inverting the seat section rearwardly in the frame when it is raised at the front thereof, and to swing the front upwardly and the intermediate section forwardly below the lower end of the back rest and above the front board in one direction of movement, spring means to balance and assist the overturning movement of the folded sections to the said raised position, stop means connected to the seat section and one of the mounting members for releasably holding the folded seat sections in the predetermined set position and a locking leg structure connected to the intermediate and outer sections for holding them releasably in the folded position and for automatically controlling the folding and unfolding movement of the legs and the said sections, the locking leg structure being unlocked when the said outer section is manually moved outwardly in a direction opposite to the said swinging movement for extending the sections into alignment with the seat section inverted within the frame and to form a bed.

10. In convertible furniture in accordance with claim 9, the seat section having a front rail in seat position which forms an extension of the fixed front board and the front board having roller means at the rear side thereof and projecting above the top to engage and guide

the front rail of the seat in alignment with the fixed front board in the folding movement of the seat and other sections within the frame.

11. In convertible furniture, the combination with a seat frame having a back rest extending downwardly and forwardly to the rear of a seat position within the frame, a fixed front board extending upwardly at the front of the frame, the space between the bottom of the back rest and the top of the front board being limited to the depth of the seat in the frame, of a sectional folding seat and bed bottom comprising connected sections foldable into a compact structure which is longer than the space between the lower edge of the back rest and the top of the front board and having a height in the frame less than the said distance between the lower end of the back rest and the top of the front board, means mounting the foldable sections to swing from a seat position with a portion of the sections behind and below the lower end of the back rest to swing the front end of the folding structure upwardly and rearwardly within the frame with the portion from behind and below the lower end of the back rest to a position above and clear of the top of the front board, and means for locking the connected sections in a compact folded position for moving them from a position within the frame to an intermediate stage in which the seat is partially inverted within the frame above the seat position and said means for locking the connected sections being released by engaging and moving one of the sections forwardly from the frame in a direction reverse to the direction of the said swinging movement to move the connected sections forwardly into alignment and over and clear from contact with the top of the front board into a bed position with one of the sections inverted in the seat position.

12. In convertible furniture in accordance with claim 11, a roller at the top of the inner side of the front board to engage and guide the connected sections in their movement into and out of the frame to prevent engagement with the top of the front board.

13. In convertible furniture in accordance with claim 11, the said means for locking the folding sections together comprising legs pivoted to intermediate and outer sections of the folded structure and a locking linkage connecting the legs to fold against the sections automatically and to unfold therefrom as the folding sections are moved into and out of the frame, and roller means at the top of the front board at the inside thereof for engaging and guiding the legs and their folding structures out of contact with the top of the front board.

14. In convertible furniture in accordance with claim 11, the means mounting the sectional folding structure for swinging movement in the frame, comprising a member pivoted at one end in the side of the frame at a position behind the lower end of the back rest and above the normal level of the seat in the seat position and the other end of the member being pivotally connected intermediate the front and rear at the side of the seat section, the seat section having a mounting member extending upwardly and rearwardly in seat position to a point below and behind the lower end of the back rest and

60

above the seat position, and another mounting member pivotally connected at one end to the said upper end of the mounting member and the other end pivoted to the frame near the bottom thereof and forwardly in the frame, the action of these mounting members being to rock the folded sections forwardly when the seat section is raised at the front thereof, those portions of the folding sections behind and below the back rest moving forwardly and upwardly in an endwise movement of the frame until the folded section is partially inverted in a position to which it is raised by the said pivotally connected mounting members.

15. In convertible furniture having a restricted space between a fixed front board and the bottom of a forwardly and downwardly extending back rest, the method of mounting a foldable seat and bed frame therein which is longer than the said space so that a portion of the frame must be housed below and behind the lower edge of the front board but is of a height less than the said space, swinging the front end of the folded sections upwardly and rearwardly so that the front end of the folded bed frames will continue upwardly and the rear end of the connected frames will swing forwardly below the lower end of the back rest to an intermediate set position between the back rest and the front board and free from contact with both of them, and unfolding the sections from their set position by moving the outer section forwardly in a reverse direction to the swinging movement over the top of the front board until the sections are in alignment with one of the sections inverted in the seat position.

16. In convertible furniture having a rigid frame with a fixed front board extending upwardly across the front of the frame, a plurality of connected seat and bed sections foldable into a hollow angular structure, the seat section forming a seat surface at the front of the frame when the sections are folded, the other connected sections folding below and behind the seat section in the frame, means mounting the seat section in the frame for swinging it and the other sections upwardly together to a predetermined set position and to invert the seat section above the frame when the other sections are swung forwardly over and clear of the front board into alignment in front of the frame, and releasable stop means connected to the seat section and said mounting means for releasably holding the folded sections together in the predetermined set position.

17. In convertible furniture in accordance with claim 16, the stop means comprising a pivoted latch attached to the seat section, and a detent fixed to said mounting means, the stop means being manually releasable to continue the movement of the connected sections.
